UNITED STATES PATENT OFFICE.

HARRY S. HART, OF CHICAGO, ILLINOIS, ASSIGNOR TO RODGER BALLAST CAR COMPANY, OF CHICAGO, ILLINOIS, A CORPORATION OF MAINE.

CONVERTIBLE-CAR CONSTRUCTION.

1,397,686.

Specification of Letters Patent.

Patented Nov. 22, 1921.

Application filed August 9, 1919. Serial No. 316,356.

To all whom it may concern:

Be it known that I, HARRY S. HART, a citizen of the United States, residing at Chicago, in the county of Cook and State of Illinois, have invented certain new and useful Improvements in a Convertible-Car Construction, of which the following is a specification.

This invention relates to convertible car constructions.

The general object of the invention is to provide a car of the Hart convertible type from which the load may be dumped to the side or to the center, or partially to the center and partially to the side.

This object is attained by providing a car having a central longitudinal stationary hopper portion, the car being provided along the sides of the floor with swinging doors mounted so that they may drop downwardly to a dumping position, raised to a horizontal position to form part of the flat floor of the dump car, or swung upwardly to an inclined position, in which case the doors form an extended wall of the central hopper.

In this particular aspect, therefore, the invention comprises a car having the stationary central longitudinal hopper portion with the swinging doors mounted along the upper outer edges of the hopper portion, which doors in one position form extensions of the hopper sides. In this embodiment of the invention the hopper sides are completed by inwardly and upwardly swinging portions which in one position form a portion of the sides of the car.

The invention is illustrated on the accompanying sheets of drawings, in which,—

40 Figure 1 is a transverse sectional view of a convertible car embodying my invention; and,

Fig. 2 is a longitudinal sectional view of the same car.

45 The various novel features of the invention will be apparent from the following description and drawings and will be particularly pointed out in the appended claims.

Referring to the figures of the drawings, 50 it will be understood that I have shown a convertible car having sides including stakes 10 which are connected at their lower ends by continuous cross beams 11 whereby the load of the car is transmitted to the sides 55 thereof. Longitudinal sills 12 are mounted

over and rest upon the cross beams 11. The body of the car includes a central stationary longitudinal hopper 13 formed by an inclined stationary side wall 14 and an inclined movable wall in the form of a door 15 whereby the load may be center dumped. When the car is used as a flat bottom car the central hopper 13 is covered. In this particular case the central hopper 13 is covered partially by members 16 which, when 60 the car is arranged as a hopper car, are used as hopper end walls spaced from the regular car end walls 17, as shown in dotted lines in Fig. 2. The remaining portion of the hopper 13 at each end is covered 65 by a movably mounted member 26, which when the car is used as a hopper car is moved over upon the floor end portion 27 as shown in dotted lines in Fig. 2. The flat floor adjacent the central hopper 70 13 is formed by longitudinally extending doors 18 which are pivotally mounted at 19 along their inner edges or along the upper outer edges of that portion of the hopper below the floor level. As shown at the 75 left hand side of the Fig. 1, the floor door 18 is arranged in a horizontal plane, in which position it is located when the car is used as a flat bottom car. The door 18 in this horizontal position, normally is arrested 80 from an upward movement by a side chord 28 located along the floor line, there being one at each side of the car acting as stops. In this connection it will be noted that the doors 18, at their outer ends, are provided 85 with a hinged portion 18a which must be folded over the door before the latter can be elevated above a horizontal position. When the car is arranged as a flat bottom car, the side doors 20 are in a vertical position 90 engaging the side stakes 10, the car sides also including stationary portions 21 located above the doors 20. When the car is arranged as a flat bottom car the load may be dumped to the sides thereof by 95 dropping the doors 18, said doors being provided with suitable operating mechanism including a chain or cable 22 and operating shaft 23 carried by the side of the car, said cable preferably passing 100 through guide castings 24 carried by the side wall doors 20.

When it is desired to change the car from a flat bottom car to a central hopper car the same is done by shifting the car side 110

doors 20 into an inclined position, as shown at the right hand side of the Fig. 1, and in which position said slide wall doors 20 are supported by pivotally mounted supporting 5 braces 25. To complete the hopper side walls the floor doors 18 first are lowered sufficiently to permit hinged portions 18^a to be swung inwardly, whereupon the doors may be swung upwardly beyond the chords 10 or stops 28 into an inclined position by means of the door operating mechanism until said doors 18 occupy substantially the same inclined plane as the other hopper portions at each side thereof. It will be 15 understood also that the temporary hopper floor portions 16 and 26 will be moved from their full line positions shown in Fig. 2 to their dotted line positions shown in the same figure. Heretofore with the central hopper 20 arrangement no provision has been made to dump a portion of the load to the sides of the car. However, by means of my improved door arrangement the doors 18 may be lowered from their inclined position in 25 which they form hopper sides to positions wherein a portion of the load will be dumped to the sides of the car. If desired, the central hopper door 15 may be opened at the same time for center dumping.

30 It is my intention to cover all modifications falling within the spirit and scope of the following claims.

I claim:

1. In a car of the class described, a central 35 longitudinally disposed stationary hopper portion, and doors hinged along the upper outer edges of said hopper portion arranged to form in one position a part of the horizontal floor of the car and span the distance 40 between said hopper edges and the sides of the car and to be swung upwardly from the horizontal position to form a portion of a hopper side.

2. In a car of the class described, a central 45 longitudinally disposed stationary hopper portion, doors hinged along the upper outer edges of said hopper portion arranged to form in one position a part of the horizontal floor of the car and span the distance 50 between said hopper edges and the sides of the car and to be swung upwardly from the horizontal position to form a portion of a hopper side, and inwardly swinging doors hinged to and forming a part of the car 55 sides in one position also forming a portion of a hopper side.

3. In a car of the class described, a central longitudinal stationary hopper portion, and floor doors hinged along the upper 60 outer edges of said hopper portion arranged to be swung upwardly to form a portion of a hopper side, said floor doors being movable from such position to dump material to the sides of the car.

65 4. In a car of the class described, a cen-

tral longitudinal stationary hopper portion, chords arranged along the side of the car at the flat floor level, and doors hinged along the upper outer edges of said hopper portion arranged to form in one position a 70 part of the horizontal floor of the car and to be swung upwardly from the horizontal position to form a portion of a hopper side, said doors normally being prevented from moving from a horizontal position to a position to form a hopper side wall by said chords, said doors being provided with hinged portions which permit the doors to be moved upwardly beyond said chords. 75

5. In a car of the class described, a central 80 longitudinally disposed stationary hopper portion, chords arranged at the sides of the car along the floor line thereof, and doors hinged along the upper outer edges of said hopper portion arranged to take an 85 inclined position to form a hopper side wall and to take a horizontal position for forming a portion of the floor, said doors having upwardly folding hinged portions which normally engage the said chords to prevent 90 upward movement of the doors beyond a horizontal position, said hinged portions being movable into a position to permit movement upwardly beyond said chords.

6. In a car of the class described, a central 95 longitudinally disposed stationary hopper portion, and doors hinged along the upper outer edges of said hopper portion arranged to form in one position a part of the 100 horizontal floor of the car and to be swung upwardly from the horizontal position to form a portion of a hopper side, said floor doors being movable from a hopper side position and also from a horizontal position for dumping material to the sides of the 105 car.

7. In a car of the class described, a central 110 longitudinally disposed stationary hopper portion, doors hinged along the upper outer edges of said hopper portion arranged to 115 form in one position a part of the horizontal floor of the car and to be swung upwardly from the horizontal position to form a portion of a hopper side, side wall doors movable into a position to form hopper side portions, and means including a flexible member for supporting the floor doors and side wall doors in the positions in which they form hopper side portions.

8. A car of the class described including 120 a body having a side wall door and a floor door which may be moved into an inclined position to form a hopper side wall, one of said doors being supported by the other in said position, and the floor door being movable from said inclined position for side dumping.

9. A car of the class described including 125 a body having a side wall door and a floor door which may be moved into an inclined 130

position to form a hopper side wall, means for supporting the side wall door in inclined position, and means associated with said side wall door for supporting the floor door 5 in said inclined position, the floor door being movable from said inclined position for side dumping.

10. A car of the class described including a body having movable side portions and 10 movable floor portions which respectively occupy vertical and horizontal positions when the car is arranged as a flat bottom car and which take an inclined position to

form a hopper side wall when the car is arranged as a hopper car, means for supporting the movable side portion in inclined position, and means associated with said side wall door for supporting the movable floor portion in said inclined position, and said floor portion being movable for side dumping from an inclined hopper position and from a horizontal position. 15 20

Signed at Chicago, Illinois, this 2nd day of August, 1919.

HARRY S. HART.
